CLAIM

The ornamental design for a food slicer, as shown and described.

DESCRIPTION

FIG. 1 is a front perspective view of a food slicer showing our new design;

FIG. 2 is a rear perspective view thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a rear elevational view thereof; and,

FIG. 8 is a bottom plan view thereof.

The broken lines in FIG. 8 illustrate portions of the design that form no part of the claim.

1 Claim, 8 Drawing Sheets
